UNITED STATES PATENT OFFICE.

FRANK L. SCHULZ, OF CHICAGO, ILLINOIS.

TIME-STAMP.

SPECIFICATION forming part of Letters Patent No. 745,244, dated November 24, 1903.

Application filed May 25, 1903. Serial No. 158,655. (No model.)

To all whom it may concern:

Be it known that I, FRANK L. SCHULZ, a citizen of the United States, residing at Chicago, in the county of Cook and State of Illinois, have invented certain new and useful Improvements in Time-Stamp; and I do hereby declare the following to be a full, clear, and exact description of the invention, such as will enable others skilled in the art to which it appertains to make and use the same.

My invention relates to a novel construction in a time stamp, the object being to provide a simple, durable, and efficient device of this character; and it consists in the features of construction and combinations of parts hereinafter fully described and claimed.

In the accompanying drawings, illustrating my invention, Figure 1 is a central vertical section of a time-stamp constructed in accordance with my invention. Fig. 2 is a plan section of same on the line 2 2 of Fig. 1. Fig. 3 is a bottom plan view of same. Fig. 4 is a fragmentary detail side elevation of same.

My said device comprises an inverted cup 25 A, on the outer face of the flange B of which a dial is imprinted. Within said flange an annular dial C, of rubber or other suitable material, is rigidly mounted, which registers with the dial on the outer face of said flange 30 B. Pivotaly mounted in said cup A concentrically therewith is a disk D, upon the lower face of which a printing pad or block E is mounted, such pad or block being provided with spaces to receive type F. Said disk is 35 further provided on one edge with a downwardly-extending projection G, provided in its free end with a wedge-shaped recess H, adapted to receive a triangular block I, which is securely clamped therein by contracting 40 said recess H and which is adapted to print a representation of the hand or pointer of a clock to indicate on the dial C. Said disk and cup are provided with corresponding annular grooves J to receive balls K, interposed 45 between said disk and said cup. Said disk is provided on its upper face with a central externally-threaded stem L, which passes through a central opening in the cup A and receives a nut M, which is adapted to bear 50 upon the upper face of said cup to adjust the disk in position therein. The upper end N

of said stem L is reduced and square and receives the inner end of an arm or lever O of greater thickness than the depth of said square end N. In the center of said stem L 55 and its square end N is a threaded recess P, which receives the threaded stem Q of the handle R, said stem Q being secured in the lower end of a rubber cylinder S, which is secured at its other end in the lower end of 60 said handle R, said rubber cylinder serving to enable an impression to be made even though the handle be not held perpendicularly to the surface to be printed upon. The free end of 65 said arm or lever O is bent over and pointed to indicate on the dial on the outer face of the flange B the position of said end of said arm corresponding in position with the pointer or block I on the disk D and indicating the same point on the dial. Adjacent the flange B said 70 cup A is provided with an annular row of recesses T, corresponding in number with the divisions of the dials and in radial alinement therewith. Said arm or lever O is provided adjacent its free end with an opening U, 75 which is surrounded by a vertical sleeve V. A pin W, provided at its upper end with a button X, passes through said sleeve and said opening U and enters said recesses T in the upper wall of said cup A, said pin being provided adjacent its lower end with a collar Y, 80 between which and the upper wall of said sleeve V a spring Z is interposed which normally holds said pin at the lower limit of its movement. It will be noted that said arm O is 85 rigid with the disk D and that its inner end is compressed upon the nut M by the stem Q, thereby serving the purpose of a lock-nut to prevent said nut M from turning.

When it is desired to set the device to print 90 the hour, the handle R is grasped in one hand and the pin W withdrawn from the recess engaged thereby, and with the other hand the cup A is revolved until the free end of the hand registers with the desired point in 95 the dial on the flange of said cup. The said pin W is then released and enters the desired recess T, thereby securely holding the disk and cup in relative positions. The said hand O is so arranged relatively to the printed 100 matter on the disk that when the impression is made so that the said hand points toward

the upper end of the sheet the impression made will read from left to right of the sheet.

I claim as my invention—

In a device of the kind specified, the combination with a central member carrying an impression - pointer, an inverted concentric cup rotatably mounted on said central member and carrying an impression - dial and a corresponding adjusting - dial, balls inter-
posed between said members, a threaded stem on said central member having a reduced square end, a nut on said stem engaging said cup, a lever of greater thickness than the depth of said square end of said stem inserted over the latter, a central threaded opening in said stem, a handle having a threaded

shank adapted to enter said opening, and having a shoulder adapted to bear on the inner end of said lever, an annular row of recesses in said cup, and devices carried by said lever adapted to enter said recesses to lock said cup against rotation, said lever being adapted to act as a pointer to indicate on the adjusting-dial of said cup, substantially as described.

In testimony whereof I affix my signature in presence of two witnesses.

FRANK L. SCHULZ.
